[57] CLAIM

What is claimed is the ornamental design for a long handled lotion applicer, as shown and described.

DESCRIPTION

FIG. 1 is a perspective view of the long handled lotion applicer of the present invention.

FIG. 2 is a bottom view of the long handled lotion applicer of the present invention.

FIG. 3 is a top view of the long handled lotion applicer of the present invention.

FIG. 4 is a side view of the long handled lotion applicer of the present invention, the other side being a mirror image thereof.

FIG. 5 is a left end view of the long handled lotion applicer of FIG. 4; and,

FIG. 6 is a right end view of the long handled lotion applicer of FIG. 4.
